UNITED STATES PATENT OFFICE.

GEORGE A. NORRIE, OF WAUKESHA, WISCONSIN.

COMBINATION CASKET AND BURIAL VAULT.

Application filed May 21, 1927. Serial No. 193,229.

This invention pertains to improvements in burial caskets, and has primarily for its object to provide a comparatively light, inexpensive, durable, and highly attractive casket, which, because of the permanent nature of its structure, will serve as a vault to prevent rapid disintegration of the corpse.

A further object of the invention is to provide a casket built up from panels of indestructible material, which will readily lend itself to any type of decoration or finish, such as plain colors, or an imitation of wood.

A further object is to provide means in combination with a casket for taking the weight of the earth from the casket to prevent collapse of the casket and settling of the ground above the same.

With the above and other objects in view, which will appear as the description proceeds, the invention resides in the novel construction, combination and arrangement of parts substantially as hereinafter described and more particularly defined by the appended claims, it being understood that such changes in the precise embodiment of the herein disclosed invention may be made as come within the scope of the claims.

Figure 1 is a transverse section taken through a casket constructed in accordance with the present invention, and illustrating the same positioned in the ground.

Figure 2 is a side elevation with parts broken away and in section.

In the accompanying drawings is illustrated one complete example of the physical embodiment of the present invention constructed according to the best mode so far devised for the practical application of the principles thereof.

Referring now more particularly to the accompanying drawings, wherein the preferred form of the invention is illustrated, the casket is designated by the numeral 1, the sides of the same being constructed from panels 2 formed from any permanent composition, such as concrete, asbestos, or the like.

The bottom 3 of the casket is preferably formed of sheet metal having vertical side extensions 4 for the reception of the side walls 2. Should it be desired to provide a more solid permanent structure, a bottom panel 5 constructed of suitable composition, may also be employed. The interior of the casket may be finished in the usual tufted

style, or with any other form of decoration that may be desired.

The upper edge of the casket is provided with a metal rim 6 having a depending lip 7 which engages the interior of the walls 2. As best shown in Figure 1, it will be noted that the rim 6 projects over the side of the casket and covers a decorative finishing or moulding, which moulding may also be applied to the bottom edge of the casket as well as the corners.

A cover 8, preferably stamped from sheet metal and arched upwardly serves as a closure for the casket, and due to the arch or dome feature, obviously the sides of the casket may be reduced in height still leaving sufficient depth for the reception of the corpse.

From the foregoing it will readily be seen that a very inexpensive and simple structure has been provided, which, when assembled, forms a practically air-tight, durable structure of a permanent nature, which is not subject to disintegration.

For receiving the weight of the earth above the casket after the same has been placed in the ground, it is proposed to employ an additional hood 9 for the top of the casket. This hood, for convenience in handling and manufacture, may be constructed in sections 10, either cast or otherwise formed from a composition of a permanent character, such as concrete or the like. Each section is provided with overlapping tongues 11 engaged in grooves 12 formed in the adjacent section. Thus, when the sections are positioned upon the top of the casket they form a continuous interlocked dome for the support of the earth above the casket.

To assist in supporting the weight of the earth above the casket, pedestals 13 formed of concrete, or other suitable material, may be used along side of the coffin at spaced intervals, preferably at the intersection of the sections 10. If desired, the pedestals 13, as well as the casket, may be positioned upon upon a base 14 of concrete, stone, or other desirable material, which will prevent settling of the casket into the ground.

Obviously, certain of the elements may be eliminated without departing from the invention, which primarily consists in the structure of the casket itself. It will also be appreciated that the present invention has all of the advantages of a cast or moulded vault or casket, with the additional ad-

vantages of being cheap in manufacture, and very light to permit the same to be utilized as a casket for the transportation of the corpse, as well as a permanent burial vault.

5 It will also be seen that any desired scheme of decoration may be employed, as the composition material employed in the sides of the casket readily lends itself to the reception of paint or other finishing materials.

10 I claim:

1. A burial casket comprising separate side wall panels formed of permanent composition material, a metal bottom for the reception of said side wall panels and having upturned edges to assist in retaining said panels in assembled relation, a bottom panel adapted to engage the inner sides of the side wall panels to securely hold them 15 against the edges of said metal bottom, a metal rim disposed upon the top edges of said side wall panels and provided with a depending lip engaging the inner sides of said side wall panels, and a domed cover 20 adapted to seat upon said rim and provided 25

with a depending lip to engage the lip of said rim to form a tight seal.

2. A burial casket comprising separate side wall panels formed of permanent composition material, a metal bottom for the reception of said side wall panels and having upturned edges for engaging the outer faces of said side walls, a bottom panel formed of permanent composition material and engaging the inner faces of said side wall panels 30 to hold the same against the upturned edges of said metal bottom, a metal rim mounted upon the top edges of said side walls and provided with a depending lip engaging the inner faces of said side walls, and a domed metallic cover adapted to seat upon said metal rim and provided with a depending lip for engagement with the lip of said metal rim to form a relatively tight connection and relieve inward strain upon the rim. 35 40 45

In testimony that I claim the foregoing I have hereunto set my hand at Milwaukee, in the county of Milwaukee and State of Wisconsin.

GEORGE A. NORRIE.
